UNITED STATES PATENT OFFICE.

DAVID CROSSLEY, OF TRENTON, NEW JERSEY.

POWER PRESS FOR TILE, MOSAICS, AND THE LIKE.

1,423,401.

Specification of Letters Patent. Patented July 18, 1922.

Application filed July 29, 1920. Serial No. 399,841.

To all whom it may concern:

Be it known that I, DAVID CROSSLEY, a citizen of the United States, residing at Trenton, in the county of Mercer and State 5 of New Jersey, have invented certain new and useful Improvements in Power Presses for Tile, Mosaics, and the like; and I do hereby declare the following to be a full, clear, and exact description of the invention, 10 such as will enable others skilled in the art to which it appertains to make and use the same.

This invention relates to power presses for forming mosaics, floor and wall tiles, and 15 analogous products from plastic materials such as clay, or any other substance.

An object of this invention is to produce a power operated press wherein ease of operation and increased production are made possible through the construction of a novel tile forming means and associated operating mechanism.

Another object of the invention is the production of a power operated press including 25 a movable die case adapted to receive the material or dust from a suitable tray positioned and moved with respect to the said case, means for compressing the material, and means for ejecting the compressed tile 30 from the case.

A further object of the invention is to produce a power press having means including a single cam of novel construction for compressing the material and then imparting a final "set" thereto; and means for automatically stopping the press after the tile has been formed and ejected from the forming die, the parts of said press being stopped in a position to be re-loaded without 40 the manipulation of other mechanism.

Another object is the production of a power press including means for easily controlling the operation of the several mechanisms, whereby an operator is not required 45 to jump upon a treadle and otherwise exert himself to effect the compression of the material or the return of the mechanism.

With these and other objects in view the invention further consists in the construction 50 and arrangement of the several parts hereinafter described and pointed out in the appended claims.

In the drawings which show an embodiment of my invention as adapted for use in forming tile, and in which corresponding 55 reference characters designate similar parts in the several views:

Figure 1 is a front elevation of the press, the treadle and clutch operated thereby being shown out of operative engagement; 60

Figure 2 is an end view looking at the right-hand end of the press;

Figure 3 is a vertical transverse sectional view on the line 3—3 of Figure 1;

Figure 4 is a similar view on the line 4—4 65 of Figure 1;

Figure 5 is a horizontal sectional view on the line 5—5 of Figure 1;

Figure 6 is a detail horizontal sectional view of the movable plunger for effecting 70 the compression of the material, taken on the line 6—6 of Figure 1;

Figure 7 is a detail vertical sectional view of the movable plunger and associated die case on the line 7—7 of Figure 6; 75

Figure 8 is a detail horizontal sectional view through the adjusting means for the plunger, taken on the line 8—8 of Figure 1;

Figure 9 is a plan view of the tile forming die case; 80

Figure 10 is a detail sectional view on the line 10—10 of Figure 11, of the actuating or clutch device for controlling the movement of the compressing plunger and the automatic stopping thereof; 85

Figure 11 is a vertical sectional view of the aforesaid plunger controlling device;

Figure 12 is a detail plan view of the cam end of the controlling lever and a portion 90 of the clutch pin operated thereby; 90

Figures 13, 14 and 15 are a series of views in sectional elevation, illustrating the variable movements of the die case and compressing plunger, as associated with the series of relatively fixed plungers; 95

Figure 16 is a detail sectional view showing the relative lost motion between the respective mating clutch members of the treadle operating device.

Generally stated the invention comprises 100 a tile forming device consisting of a series of relatively stationary plungers or posts against which the tiles are compressed, a movable die case surrounding the said posts,

and a compressing plunger movably associated with the die case; means for controlling the movements of the tile forming device whereby a preliminary and final compressing "set" is given the material; and means for ejecting the compressed product from the tile forming device.

The formation of the tile will be best understood by referring to Figures 13, 14 and 15. In Figure 14 the stationary plungers and movable die case are shown as positioned to form the plastic material or dust receiving compartments, the die case being in its uppermost position for receiving a maximum charge of material to be compressed. In Figure 15 the compressing plunger has been moved down upon the die case, for further movement in unison with the die case to effect the compressing of the material therein as shown. In Figure 13 the compressing plunger has been withdrawn or moved upwards, and the die case further depressed, thereby permitting the stationary plungers to eject the compressed product.

The operating mechanism of the press has been associated with the aforesaid movable die case and compressing plunger to effectively control their movements in a substantially automatic manner for rapidly forming the tile, as will be hereinafter set forth.

Referring to the drawings the press comprises among other things a suitable base 1 having secured thereto supporting standards or uprights 2, upon which latter is mounted the bed or table 3. Extending upwardly from the bed 3 are spaced supporting standards 4, which constitute the support for the cam shaft and associated mechanism to be presently described. A yoke 5 is designed to join the standards 4 as shown, thereby insuring maximum stability to the press.

Bearings 6 are formed at the juncture of the yoke 5 and standards 4, and are designed to receive the cam shaft 7 upon which is secured the compressing cam 8. Suitable stay-bolts 9 are provided to secure the yoke 5 and standards 4 to the bed of the press and the lower supporting uprights 2 as shown. (See Figure 4.) These stay-bolts extend through bosses 10 provided on the half bearings of the yoke 5.

The cam 8 is arranged intermediate of the side members of the yoke 5, and positioned centrally of the press as shown. Set-screws 11 are provided for effecting the relative adjustment of the cam 8 upon the shaft 9 as will be understood. The aforesaid location of the cam 8 with respect to the plunger is an important factor in the construction of the press in that an even pressure is imparted to the plunger at a central point as distinguished from a multiplicity of separate points, through the operation of a plurality of spaced cams, as has been the practice heretofore. The location of the cam 8 also serves

to reduce the vibration and stabilize the press. The tendency of the single cam and associated parts to unevenly wear and wobble is also reduced to a minimum.

The periphery of the cam 8 is provided with recesses 12 into which are positioned blocks 13 of relatively hard material such as steel, for example. Each block 13 is provided with a raised surface 14, said surfaces constituting the high points of the cam, designed to impart a relative preliminary and final setting of the plastic material in the tile forming device. One of the blocks 13 is slightly higher than the other, thereby transmitting to the tile forming device two compressing operations. The first of these compressing operations is designed to give the preliminary set to the plastic material whereby the accumulation of air for instance is completely eliminated. The second operation is to impart the final set to the material for producing the completed tile.

The transmission of this double compressing action to the tile forming device is obtained through a novel form of compressing plunger 15, and associated parts now to be described.

Referring to Figure 7, the plunger 15 is carried by a vertically movable carriage 16 slidably mounted in a frame support 17 secured to the standards 4. This frame support may be formed of front and back sections 18 and 19, respectively, to facilitate the assembling of the parts as will be understood.

A roller 20 is provided on the carriage 16, and more particularly upon an adjustable support 21 including the screw-threaded extension 22. An adjusting nut 23 is provided on the screw-threaded extension 22 and provides for vertical adjustment. The nut 23 is held stationary within the carriage 16 and is provided with gear teeth 24 designed to mesh with a worm 25 suitably journaled in the carriage 16. The worm is provided with a squared end 26, and is designed to receive a suitable operating device for effecting the vertical adjustment of the carriage 16, and in turn the plunger 15 carried thereby.

The plunger 15 is preferably formed of suitable plates 27, the lower one of which constitutes the compressing surface cooperatively associated with the die case, and the upper one of which is movably spaced with relation to the lowermost edge of the carriage 16. These plates 27 move in unison and are carried by a suitable stem 28 arranged to extend upwardly through a bushing 29 suitably held within the carriage 16 by the pin 30. The plunger is provided with a head 31, and a key 32 is preferably provided for maintaining the alinement of the plunger as will be understood.

By this construction it will be seen that the compressing plunger is loosely mounted

with relation to the supporting carriage 16, thereby permitting a more effective transmission of the compressing force, and the proper maintaining of the lower plate 27 against the die case.

The means for maintaining the roller 20 in contact with the compressing cam 8, comprises weights 33 provided on arms 34 pivoted at 35 to the supporting standards 2. 10 (See Figure 4). Adjustable connections in the form of rods 35 are connected to the arms 34, and extend upwardly, being secured at their upper ends to levers 36 as clearly shown in Figure 7. The levers 36 are preferably mounted in roller or ball-bearing supports 37 secured to the supporting frame 17. Links 38 connect the opposite ends of the levers 36 to the vertically movable carriage 16. From this construction it will be seen that the 20 weights 33 serve to pull the connections 35 downwardly thereby causing the levers to rock upon their pivots and in turn maintain the roller 20 in constant contact with the cam 8.

25 The tile forming means, of which the aforesaid plunger 15 is a component part, includes a die case 39, and a plurality of relatively stationary plungers or posts 40. As shown in my present embodiment of the invention, the die case comprises a plate, perforated as best shown in Figure 9 to form relatively small hexagonal tiles. The die case is provided with extensions 41 to which are secured rods 42, the latter serving to vertically guide the die case by extending through the bed 3 and suitable sleeves 43 secured thereto. To the lower ends of the rods 42 a yoke or cross head 44 is adjustably secured, the said cross-head serving to impose vertical movement to the die case in an effective manner as will be presently described.

The stationary plungers or posts 40 extend upwardly from a base plate 45 secured 45 to the bed 3. These plungers are provided with heads 46 of a shape corresponding to the perforations in the die case. It will be understood that while I have shown in the present case a hexagonal form of tile forming device, that many other shapes may be used, and I do not limit myself to the size, shape or number of the posts and plastic material receiving compartments of the tile forming device.

55 The means for cooperatively moving the die case with relation to the stationary posts comprises a rack 47 provided on a rod 48, the upper end of which is secured to the cross-head 44 above referred to. The rod 48 is vertically movable in a suitable sleeve 49 as shown, and has meshing therewith a segment 50.

The segment 50 is secured to the shaft 51, suitably journalled in bearings 52 projecting 60 from the base 1 of the machine. Intermedi-

ate bearings 53 are also provided for the shaft 51, the aforesaid sleeve 49 and the support for said bearings 53 being preferably formed integral, thereby adding to the rigidity of the press at this point.

70

A clutch member 54 is slidably mounted on the shaft 51, and is designed to engage a mating clutch member 55 secured to the shaft 51. The clutch member 54 is operatively controlled by means of a treadle 56 suitably pivoted at 57 and connected by means of a link 58 to the clutch member as shown. A weight 59 is provided on the treadle and serves to normally keep the clutch member 54 out of engagement.

80

The clutch member 55 is provided with an extension or arm 60, to which is adjustably secured one end of an eccentric rod 61. An eccentric strap 62 is provided at the upper end of the rod 61 and encircles a suitable eccentric 63 secured to the main shaft 64.

85

It will be seen from the construction of the parts just described that motion is transmitted to the clutch member 55 in a manner for continuously oscillating the said clutch member during the operation of the press. It will be seen that when an operator engages the clutch member 54 with the clutch member 55 by pressing down on the treadle 56, that movement will be transmitted to the segment 50 and in turn to the die case.

90

The construction of the mating lugs of the clutch members 54 and 55 is such, as to permit of sufficient lost motion between the lugs to prevent the transmission of an oscillatory movement of the clutch member 55, the result being that but positive movement is imparted to the segment and in turn to the die case. The effect of this movement is to elevate the die case with respect to the stationary plungers and thereby present the material receiving openings for filling.

100

The main shaft 64 is suitably journalled in bearings 65. These bearings are carried by suitable arms or brackets 66 projecting from the standards 4. An additional bearing 67 is provided at one end of the machine in an arm 68 projecting from an outwardly and upwardly extending bracket 69 secured to one of the standards 4.

115

A pinion 70 is keyed to the main shaft 64, and has meshing therewith a relatively large gear 71. The gear 71 is loosely mounted upon the cam shaft 7, and is designed to be continuously revolved.

120

A novel clutch mechanism is interposed between the loosely mounted gear 71 and the compressing cam 8, whereby an operator positively controls the formation of the tile.

125

Referring to Figures 1 and 2, this controlling device comprises a hand lever 72 pivotally supported at 73 to the bed 3. The end of the lever 72 is connected to a vertical rod 74, preferably off-set as shown, the upper end of said rod being connected at 75 with a

130

lever 76. The lever 76 is pivoted at 77 and is provided with a nose 78 adapted to control the clutch mechanism referred to.

Referring to Figures 10, 11 and 12, this clutch comprises a collar 79 adjustably secured to the cam shaft 7 as shown. A spring-pressed pin 80 is slidably mounted in the flange 81 of the collar 79, and is adapted to extend therethrough and engage one of a series of pins 82 secured to and extending from the large gear 71. A spring 83 held in place by means of a screw 84 serves to yieldingly position the pin 80 within the collar as shown. The pin 80 is provided with a lip 85 having a beveled surface 86 cooperatively associated with a beveled surface 87 formed on the nose 78 of the lever 76 hereinbefore described.

In operation it will be seen that as the nose 20 of the lever is withdrawn from between the lip 85 of the pin and the flange 81 of the collar, that the spring 83 will force the said pin outwardly into the space between the gear 71 and the collar, thereby permitting it to engage one of the series of projections 82 carried by the gear 71. When thus engaged, motion is transmitted from the gear to the collar and is in turn imparted to the compressing cam 8 for forming the tile. 30 The spring 89 encircling the rod 74 of the controlling device serves to immediately return the lever 76 and more particularly the nose 78 thereof, into the path of the revolving lip 85 provided on the pin 80, and 35 as soon as the beveled faces of the lip and nose contact as shown in Figure 12, it will be seen that the pin 80 is withdrawn from engagement with the projection 82 and the revolving of the cam shaft stopped. Thus 40 it will be seen that in forming each series of tiles, that but a single revolution of the cam shaft is utilized, and further that the stopping of the press after forming the said tiles is automatically provided for.

45 A suitable friction controlling device 90 may be provided for contacting with the periphery of the flange 81 as shown.

The tile ejecting means is controlled by an eccentric 91 operable upon the cam shaft 7, 50 and having a rod connection 92 secured to an arm 93 extending from the shaft 51. The timed relation of the parts is such that upon the completion of the tile compressing operations, the die case is moved downwardly 55 until the heads 46 of the posts are flush with the top of the said die case, see Figure 13, during which movement the tiles are ejected from the forming openings and are ready to be removed by an operator.

60 The main shaft 64 is provided with the usual pulleys 94 for imparting power to the press from any suitable source, (not shown). Supplemental supporting rods 95 are interposed between the bed 3 of the press and the 65 casting or housing forming the bearing sup-

port 53 as best shown in Figure 1. Other strengthening and bracing devices may also be used, and I do not limit myself to the exact construction of the several supporting frame parts herein shown.

70 In operation, and assuming the die case to be all the way down from a prior ejecting of the compressed tile, an operator positions a tray containing the plastic material or dust upon the die case moving it until it 75 covers the several tile forming openings. In this position the operator places his foot upon the treadle 56 and engages the clutch members 54 and 55, thereby causing the eccentric 63 to impart motion to the shaft 51 80 and in turn to the die case through the segment 50 and rack 47.

This operation causes the die case to move upwardly to form the material receiving compartments into which latter is deposited 85 the dust from the tray. The material having been deposited in the die case as shown in Figure 14, the operator withdraws the tray over the top of the die case to starting position, smoothing the deposits of dust in 90 the several tile forming compartments as will be understood.

95 The starting lever 72 is now grasped and pulled outwardly sufficiently to withdraw the nose 78 of the lever 76 to allow the pin 80 to move inwardly and engage one of the projections 82 of the gear 71, thereby imparting rotary movement to the cam shaft 7 and in turn causing the compressing cam to revolve in the direction of the arrow 100 shown in Figure 3, and successively compress the material in the preliminary and final manner as hereinbefore described. During this operation it will be apparent that the weights 33 serve to keep the roller 105 20 against the periphery of the cam, and further that the loose mounting of the plunger 15 prevents any tendency of the said plunger to move away from the die case during the interval between the preliminary 110 and final compressing operations produced by the high points on the cam.

115 The relative movement of the die case and compressing plunger in a downward direction is such that the material is finally compressed to a thickness shown in Figure 15.

120 It will be understood, however, that adjustments can be made to permit of the formation of tile of varying thicknesses. For instance, the die case 39 can be moved 125 a greater or less distance by loosening the nuts and adjusting the rod 61 connected to the arm 60, which adjustment will increase or diminish the capacity of the material receiving compartments in the die case. The adjustment of the compressing plunger 15 within the sliding carriage 16, may also be made as has been hereinbefore mentioned.

130 Upon the completion of the compressing

operations, the plunger 15 is caused to recede from the die case, whereupon the eccentric 91 through its connection with the shaft 51 will cause the segment 50 to lower the rack 47 and in so doing bring down the die case for the ejecting of the compressed tile.

The cam shaft has now substantially completed one revolution, and with the nose 78 of the lever 76 in its returned position through the action of the spring 89, it will be seen that the lip 85 is engaged by said nose and the pin 80 withdrawn from engagement with the projection 82 on the gear 71, thereby causing the press to automatically stop.

The operator now moves the tray across the die case pushing the compressed tile on to suitable receiving means. By this movement the tray is again in position for depositing the material into the die case, and the foregoing operations are again repeated in the production of another series of tiles. A leveling means consisting of adjustable screws 96 is provided for adjusting the die case as shown.

From the foregoing it will be obvious that an operator is enabled to greatly increase the production of a machine constructed in accordance with this invention for the reason that little time, if any, is lost in removing the compressed tiles and positioning the tray for producing another set of tiles. It will also be apparent that the operator can easily position the die case by merely pressing the treadle, and then pulling the controlling lever, both of which devices are designed to automatically disengage the operating mechanism for bringing the press to a standstill upon the completion of one revolution of the cam shaft and the compressing of the tiles.

While I have shown the press as primarily designed for use in producing tile, it will be understood that various changes in the construction and arrangement of the several parts may be resorted to for the production of other compressed articles, and I do not limit myself to the exact structural details herein set forth.

I claim:

1. A power press of the class described including in combination a forming device composed of a series of stationary members, a die case surrounding said members, means for raising said die case, said means including a clutch and counterbalanced treadle, means including a shaft and plunger for compressing the material to form the tile and means for lowering said die case for ejecting the compressed material, said last mentioned means being operated from the said shaft independently of the said raising means.

2. A power press of the class described

including in combination a forming device comprising a series of stationary members, a die case surrounding said members, a shaft, means interconnected with said shaft for raising said die case, means for compressing the material to form the tile, said means including a plunger and actuating shaft therefor, and means for lowering the said die case for ejecting the compressed material, said means being interconnected with and operated by the said actuating plunger shaft.

3. A power press of the class described including in combination a forming device composed of a plurality of stationary members, a die case surrounding said stationary members, means for raising said die case from normal position with the top face thereof flush with the said stationary members to form material receiving compartments, a compressing plunger cooperatively associated with said die case, means for moving said plunger, means for relatively moving the die case downwardly during the compressing operation, and means including the last mentioned means for lowering the die case flush with the said stationary members for ejecting the compressed material.

4. A power press of the class described including in combination a forming device composed of a plurality of stationary members, a die case surrounding said stationary members, means for raising said die case from normal flush position with the top of said stationary members to form material receiving compartments, a compressing plunger cooperatively associated with said die case, means including a shaft for moving said plunger, and means for lowering said die case flush with the tops of said stationary members for ejecting the compressed material, said last mentioned means being operatively controlled by the aforesaid shaft.

5. A power press of the class described including in combination a forming device having a material receiving compartment formed of a stationary member and a surrounding die case into which the stationary member extends, means for raising said die case, a treadle for actuating said means, means for moving the die case for compressing the material within the aforesaid compartment, and means for lowering said die case for ejecting the compressed material, said last mentioned means being operated independently of said treadle and immediately following the compression operation.

6. A power press of the class described including in combination a forming device having a material receiving compartment formed of a stationary member and a surrounding die case into which the stationary member extends, means for raising said die case from normal flush position with the top of said stationary member, and means for moving the die case for compressing the

material within said compartment, said means also serving to finally lower the said die case flush with the top of said stationary member for ejecting the compressed material.

7. A power press of the class described including in combination a forming device having a material receiving compartment formed of a stationary member and a surrounding die case into which the stationary member extends, means for raising said die case from normal flush position with the top of said stationary member, a compressing plunger adapted to move against and away from said die case, means for moving said plunger against and away from said die case, and means including a positively actuated eccentric and cam for moving said die case and plunger while engaged, for compressing the material, said eccentric means also serving to lower the die case flush with the tops of said stationary members for ejecting the compressed material when the plunger moves away from the die case.

25 8. A power press of the class described including in combination tile forming means comprising a movable die case and compressing plunger, a shaft provided with a cam for moving said plunger toward and against the die case, means for moving said plunger away from the die case, means for rotating said shaft, and means including a clutch for stopping the rotation of said shaft and cam after each revolution thereof.

35 9. A power press of the class described including in combination tile forming means comprising a movable die case and compressing plunger, means for raising said die case, means for lowering said die case, both of said means being interconnected for continuous operation to form the product, and means including said movable die case for ejecting the compressed material, said last named means being interconnected with the means for raising the die case and the means for lowering the die case aforesaid.

10. In a power press of the class described the combination with a product forming die composed of relative stationary and movable members, a compressing plunger cooperatively associated with the movable member, means for imparting a plurality of compressing operations to the product within the die, and means including a plurality of eccentrics for variably moving said compressing plunger and the aforesaid movable member of the forming die in a continuous cycle of power operations with said compressing means, whereby the compressed product is ejected and the said movable die member stops flush with said stationary die member.

11. In a power press of the class described the combination with a product forming device composed of relatively fixed and mov-

able die members, means cooperatively associated with the movable die member for pressing the material, operating means including a clutch for positioning the movable die member with respect to the stationary die member to receive the material, and an eccentric for returning the movable die member to normal position.

12. In a power press of the class described the combination with a product forming device composed of relatively fixed and movable die members, a movable plunger cooperatively associated with the movable die member for pressing the material, a cam for imparting a plurality of compressing movements to the plunger, a shaft for said cam, an eccentric adapted to position the movable die member to receive and compress the material, and another eccentric for further positioning the movable die member for ejecting the compressed product.

13. In a power press of the class described the combination with a product forming device composed of relatively fixed and movable die members, a movable plunger cooperatively associated with the movable die member for pressing the material, a cam for imparting compressing movement to the plunger, operating means for said cam, and means for disengaging the cam from the operating means for stopping said cam after each revolution thereof.

14. In a power press of the class described the combination with a product forming device composed of relatively fixed and movable die members, a movable plunger cooperatively associated with the movable die member for pressing the material, a cam for imparting compressing operations to the plunger, operating means for said cam, a clutch between said cam and operating means, and means for automatically disengaging the clutch after each revolution of the cam.

15. In a power press of the class described the combination with a product forming device composed of relatively fixed and movable die members, a movable plunger cooperatively associated with the movable die member for pressing the material, means including a single cam having a plurality of high points for imparting successive compressing operations to the plunger, means for maintaining the plunger in constant contact with the movable die member during the revolving of the cam, and means for stopping said cam after each revolution thereof.

16. In a power press of the class described the combination with a product forming device composed of relatively fixed and movable die members, means for adjusting said movable die member, a movable plunger cooperatively associated with the movable die member for pressing the material, and

means for adjusting said plunger with respect to the adjustment of the aforesaid movable die member.

17. In a power press of the class described
5 the combination with a product forming device composed of relatively fixed and movable die members, and means for compressing the material, said means including a loosely mounted plunger cooperatively associated with the aforesaid movable die member, a movable carriage for supporting said plunger and a screw for vertically adjusting said carriage.

18. In a power press of the class described
15 the combination with a product forming device composed of relatively fixed and movable die members, means for compressing the material, said means including a movable support, a plunger loosely mounted in said support and cooperatively associated with the aforesaid movable die member, a cam for moving said support and plunger, and means including a pivoted lever having one end connected to said plunger, a weight
20 interconnected with the other end of said lever and adapted to maintain the aforesaid movable support in contact with said cam.

19. In a power press of the class described
25 the combination with a product forming device composed of relatively fixed and movable die members, means including a loosely

mounted plunger cooperatively associated with the movable die member for compressing the material, operating means for said plunger, and means including a plurality of levers and a weight for maintaining the said plunger in contact with the aforesaid movable die member during the compressing of the material.

20. In a power press of the class described
35 the combination with a product forming device composed of relatively fixed and movable die members, means including a support, a carriage movable in said support, an adjustable roller provided on said carriage, a loosely mounted plunger in said carriage cooperatively associated with the movable die member for compressing the material, and operating means for imparting a plurality of compressing movements
40 to said roller, and means permitting said plunger to remain in contact with the movable die member during the imparting of the plurality of aforesaid compressing movements.

55 In testimony whereof I affix my signature, in presence of two subscribing witnesses.

DAVID CROSSLEY.

Witnesses:

DONALD M. MILLER,
THOMAS W. HOULROYD.
